(74) *Attorney, Agent, or Firm* — Steven N. Fox, Esq.

(57) **CLAIM**

The ornamental design for a ruler foot, as shown and described.

DESCRIPTION

FIG. 1 is a perspective left side view of a ruler foot according to the present invention;
FIG. 2 is a perspective right side view of the ruler foot;
FIG. 3 is a left side view thereof;
FIG. 4 is a right side view thereof;
FIG. 5 is a top view thereof;
FIG. 6 is a bottom view thereof;
FIG. 7 is a front view thereof;
FIG. 8 is a rear view thereof; and,
FIG. 9 is a top view taken from line 9-9 of FIG. 3.
The dash-dot-dot lines on the drawings are included as boundary lines and form no part of the claimed design.

1 Claim, 9 Drawing Sheets
